(57) **CLAIM**

The ornamental design for a turf aerator, as shown and described.

DESCRIPTION

This application is being filed contemporaneously with application for U.S. Letters Patent Ser. No. 10/604,088, entitled Turf Aerator with Unibody Construction and Reciprocating Tines, which is hereby incorporated by reference herein.

FIG. 1 is a perspective view of a turf aerator embodying my design, with the engine, wheels, cylindrical tines and other details of construction being shown in broken lines for illustrative purposes only and forming no part of the claimed design;

FIG. 2 is a front elevational view of the turf aerator illustrated in FIG. 1;

FIG. 3 is a side elevational view of the turf aerator illustrated in FIGS. 1-2;

FIG. 4 is a rear elevational view of the turf aerator illustrated in FIGS. 1-3; and,

FIG. 5 is a plan view of the turf aerator illustrated in FIGS. 1-4.
